UNITED STATES PATENT OFFICE.

THORNTON B. BARNES, OF NEW YORK, N. Y.

EMBALMING PROCESS.

1,318,957.

Specification of Letters Patent.

Patented Oct. 14, 1919.

No Drawing.

Application filed September 10, 1917. Serial No. 190,618.

To all whom it may concern:

Be it known that I, THORNTON B. BARNES, a citizen of the United States, and a resident of the city of New York, borough of 5 Manhattan, in the county and State of New York, have invented a new and Improved Embalming Process, of which the following is a full, clear, and exact description.

This invention relates to embalming or 10 preservation of corpses or flesh of bodies of inferior animals and has particular reference to the embalming art having in view a number of practical results heretofore unknown.

15 Among the objects therefore of this invention is to provide a process for embalming which shall result in the restoration to the body of a more natural or life like appearance than usual.

20 Another object of the invention is to provide a more thorough distribution of the antiseptic or disinfectant fluid or fluids whereby the same may be caused to reach throughout the minutest portions of the 25 body, than can be accomplished by other known processes.

A still further object is to provide a process through the practice of which a more 30 thorough desiccation of the skin, with the natural preservative results thereof, may be realized.

The foregoing and other objects of this invention will be hereinafter more fully set forth and claimed, and while I may 35 specify more or less definitely certain steps I wish it to be understood that such specification of steps of the process are to be understood as suggestive rather than obligatory in practice.

40 Ordinarily in a corpse the veins, capillaries and arteries, constituting the vascular system, are apt to be more or less filled, occluded or obstructed with blood, which as a result of decomposition or stagnation soon 45 becomes dark or discolored, constituting one of the immediate causes of the unnatural appearance of the subject. This condition of the blood in the vascular system serves not only as a direct means or cause of dis- 50 coloration of the body, but even more constitutes an obstruction preventing the free flow or distribution of the embalming fluid injected into the vascular system according to the present well known practice of em- 55 balming. It follows, therefore, as an im- mediate result that the embalming fluid,

while more or less effective with respect to all tissues reached thereby, is kept by the blood from reaching those remote tissues or portions of the body requisite for thorough 60 embalming or preservation of the flesh.

In the practice of my invention therefore I employ, in general, two steps in any desired proper sequence with respect to each other. One of these steps is to inject into 65 the body, through either the vascular system or respiratory organs, or both, a suitable gas such as air, oxygen, or the like, for bleaching by oxidation, or carbon monoxid or the like for bleaching by deoxidation, having in 70 view the bleaching or restoration to normal appearance of the discolored tissues or blood clots. In addition to the bleaching or cosmetic effect on the tissues just referred to, another important effect is accomplished, 75 namely the dilation or enlargement of the canals so that any blood or the like that may be located in the same will not seriously obstruct and prevent the free flow or complete distribution of any liquid or embal- 80 ing fluid that may be introduced. Hence the second general step in the process is to introduce into the body any suitable liquid injection having germicidal or disinfectant 85 value such as formaldehyde which produces a reaction on the blood or tissues being bleached or treated in connection with the bleaching agent used and also in connection with the blood or other tissues. Oxygen, either free or as an element of the 90 air, acts as a bleaching agent, but the results are not stable unless modified by the other steps or sub-steps of my process. However, carbon monoxid and formaldehyde combined with the blood form a stable but 95 complex and undeterminate compound, the exact chemical structure of which I am unable to specify, and while I know from my experience that the results obtained are as set forth herein no one has yet been able to 100 determine with any degree of satisfaction just what the chemical reaction or its formula is. While the order or sequence of the process or the steps of the process is not invariable, the best and most satisfactory 105 results are obtained when the gas is injected first.

As a corollary to the introduction of the bleaching or natural color developing gas or gases, I also inject, by any suitable ap- 110 pliance well understood in this art, and either through the vascular system or re-

- spiratory organs, a gas or combination of gases having either an antiseptic property or one serving to retard decomposition or else a disinfectant or germicidal property.
- 5 As illustrations of suitable gases for this purpose the following may be noted: chlorin gas, carbon monoxid, sulfurous acid gas, formaldehyde gas, smoke from burning wood, or the like.
- 10 In recognition of the well known fact that the thorough drying or desiccation of the skin of the corpse is essential for its perfect preservation, it follows that the injection of certain gases such as air, carbon monoxid, 50 chlorin or formaldehyde in the manner above indicated has a direct desiccating action upon the skin.
- 15 If the injection of the gas or gases precedes the injection of the liquid embalming fluid, one of the results of the prior injection is to dilate, enlarge or sweep the impediments or obstacles of the canals or vessels so that when the liquid disinfectant fluid is injected the latter shall have free course and 55 thus be made to reach throughout the entire system and the remotest tissues of the body. While certain of the gases such as air or oxygen if used for the purpose of bleaching or restoring the natural color might have a 60 tendency to cause or accelerate decomposition, yet this tendency is more than counteracted by the antiseptic or disinfectant properties of the other gases or embalming fluids used as a part of the same process. Moreover 65 the bleaching and desiccating effect of such gases is not neutralized by the disinfectant or preservative functions of the other elements.
- 70 I am aware that it has been proposed 40 heretofore to employ carbon monoxid or sulfurous acid gas as a bleaching agent in embalming processes for the cosmetic effect in restoring the tissues to a normal or natural color. I am also aware that others have 75 proposed to use in embalming processes various chemicals or commodities, having certain antiseptic properties when used in sufficient quantities, such as alum, corrosive sublimate, alcohol or the like, which substances, however, so far as I am aware do not possess the disinfecting or preservative effect that I am able to accomplish by my process wherein I employ in succession an injection of carbon monoxid which acts to displace oxygen thereby reducing or driving off a certain amount of moisture present especially near the skin and in the blood leaving carbonized blood or tissue that will combine readily with the ptomains or putrefactive alkaloids which when followed up 80 immediately with such a disinfectant as formaldehyde in sufficient quantities produce what I believe to be a true chemical compound of a complex nature, the formula for which I am not able to specify, but which cannot be neutralized by the addition or development of further ptomains. In other words in my process I am able by the successive application or introduction of carbon monoxid and formaldehyde to produce a 85 new chemical reaction and result never heretofore accomplished and which has not been suggested by any of the prior chemicals or processes heretofore known or practised.
- I claim:
- The herein described process of embalming which includes the injection into the body of gaseous substances including carbon monoxid serving to restore the tissues to natural cosmetic color, and injecting into 90 the body a liquid disinfectant such as formaldehyde, the carbon monoxid and the liquid disinfectant combining with each other and with the blood and tissues to form a substance unneutralizable by the addition or development of further ptomains, putrefactive alkaloids, or peptones.
- THORNTON B. BARNES.
